WRINGER HEAD MECHANISM

Fred A. Parish, Newton, Iowa

Application October 15, 1934, Serial No. 748,275

6 Claims. (Cl. 68—249)

This invention has reference to a wringer and wringer head mechanism and particularly to the controls thereof.

The main object of the invention is to provide easy and convenient controls for all the wringer functions and to interlock these controls to make the wringer operation safer than the conventional wringer.

Another object is to provide a clutching mechanism operated by release movements of the wringer mechanism the same having operative connection with a manual control element whereby rotation of the wringer rolls may be started or stopped by manipulation of manual control means, or automatically stopped by release movement.

Another object is to provide co-operative connection between the clutching mechanism and wringer post locking devices whereby when the post lock devices are operated to permit swinging movement of the wringer, rotation of the rolls is automatically stopped.

A further object is to provide an arrangement of mechanism whereby when rotation of the wringer rolls is stopped by means of release movement it can not again be started by manual means until after the roll pressure mechanism has been reset.

An additional object is to provide that when rotation of the rolls is stopped by means of unlocking of the post lock, manipulation of the manual control means is required to bring about resumption of rotation.

Additional objects will be set forth in the following description and accompanying drawings in which:

Fig. 1 is a fragmental, sectional, side elevational view of a wringer head mechanism showing an embodiment of my invention;

Fig. 2 is a view similar to Fig. 1 showing several parts in operated position as will be referred to;

Fig. 3 is a view similar to Fig. 1 showing additional parts in operated position, also to be referred to;

Fig. 4 is an end elevational view taken from line 4—4 in Fig. 1 and

Fig. 5 is a plan view taken from line 5—5 in Fig. 4.

Fig. 1 discloses the mechanism as generally comprising a wringer post 10 which carries a flanged collar 11 and which is adapted to rotatably support a wringer head structure 12.

The flanged portion of collar 11 is provided with a series of openings 13, so disposed as to align with a pin member 14 which is slidably supported

in head structure 12 and urged to enter openings 13 by a spring 15. It will be obvious that with pin 14 engaged in an opening 13 as in Fig. 1 the wringer head is securely locked against rotation upon post 10, whereas with the pin in raised position as in Fig. 2 the head may be freely rotated. This feature will be referred to later.

Rotatably supported in structure 12 is a vertical shaft 16 to which a bevel gear 17 is secured. Gear 17 meshes with dual oppositely disposed gears 18 and 19. Shaft 16 has connection at its lower end with a power source, not here shown, by means of which the shaft and gears mentioned are continuously rotated.

Gears 18 and 19 have their hubs journaled in structure 12 by means of which they are rotatably supported and adapted to rotatably support a floating shaft 20, the end of which extends toward the roll assembly for a purpose to be described.

A toothed clutch member 21, having a continuous groove 22 formed about its periphery is slidably mounted in keyed relation upon shaft 20 between gears 18 and 19 and the teeth of the clutch member are adapted to engage teeth 23 of either of the gears to rotate shaft 20 in either direction or to remain in central neutral position as shown in Fig. 1.

A stub shaft 24 is journaled in the upper portion of structure 12 and is provided at its upper end with a handle assembly 25 by means of which it may be rotated. The lower end of the shaft is provided with an eccentrically disposed stud 26 extending into groove 22 of clutch 21. A roller 27, mounted on the stud, engages the sides of the groove and is thus effective, when handle 25 is rotated, to move the clutch into engagement with one of gears 18 or 19 to bring about rotation of shaft 20 in selected rotation, or to retain the clutch in neutral position.

A ball 28, mounted in structure 12 is urged by a spring 29 to engage suitably disposed indentations in the head portion of handle 25 whereby shaft 24 and clutch 21 are retained in selected position.

Fragmental portions of a roll wringer structure are shown in the several views. Since this structure is not an important part of my invention, it will not be described further than to say that 30 designates a lower portion of the wringer frame, 31 an upright portion of the same and 32 a movable top portion thereof. A lower roll 33 is supported in upright 31 by means of a bearing block 34 and the upper roll 35 is supported by means of a bearing block 36 which is slidably

mounted in the upright. A tensioning spring 37, supported in frame portion 32, forces bearing block 36 downwardly with the result that roll 35 is resiliently held in pressure relation with lower 5 roll 33.

Frame portion 32 is shown as held in position upon upright 31 by means of an arm member 38 which is pivotally supported at 39 upon upright 31. The arm is fashioned to have a hook portion 40 extending around the upper side of frame portion 32, and the hook is provided with an upstanding lip portion 41. Lip 41 is engaged by a complementary hook portion 42 of a latch member 43. Member 43 is pivotally mounted at 44 on frame 32 and has a backwardly extending portion 45 by means of which it may be manipulated.

With the parts in position shown in Fig. 1, the arm 38, retained by latch 43, is obviously effective to retain frame 32 against upward movement, which movement would normally be produced by action of spring 37 abutting the bearing 36.

Fig. 3 illustrates the movement of frame 32 resulting from releasement of arm 38 as brought 25 about by manipulation of latch member 43.

Fig. 3 also more clearly discloses a link member 46 pivotally attached at 47 to frame 32 and extending downwardly within upright 31.

Secured upon link 46 is a lug 48 and disposed 30 in the path of this lug is a forked extending portion 49 of a lever 50. The opposite leg of the forked extending portion is set back somewhat as shown in Fig. 3, and has an extending outwardly directed portion 49', the purpose of which will be 35 described.

Lever 50 is pivotally supported at 51 upon structure 12 and has a forked portion 52 extending upon either side of a plunger member 53.

Plunger 53 is slidably supported in structure 12 40 as shown, and is provided with a groove 54 which is adapted to engage a ball 55, Fig. 4, propelled by a spring 56, both retained in a cavity in structure 12. The ball is obviously adapted to temporarily retain plunger 53 in a predetermined 45 position as will be noted later. A knob 53' facilitates manipulation of the plunger.

A coil spring 57 reacts between structure 12 and lever 50 to urge the same toward the operated position shown in Fig. 3.

Reference has already been made to a pin member 14 adapted to lock the wringer head upon post 10.

The pin is manually operated by means of an extending arm 58 engaging a cross pin 59 secured 55 in member 14. Arm 58 is secured upon a transverse shaft 60 which latter is journalled in structure 12.

A handle member 61 is secured to an extending end of shaft 60 by means of which the arm 58 is 60 moved to bring about the described movement of pin 14.

An arm 62 is also secured to shaft 60 and carries a lug 63 which engages in a slot 64 formed in the lower end of a link 65 which extends upwardly and has its upper end supported by a shoudered portion of plunger 53.

A nut or collar 66, secured to the plunger, confines link 65 and also forms a head adapted to engage an arm of a lever member 67 which is 65 pivoted at 51 and has downwardly extending arms 68 carrying inwardly disposed lugs 69.

Lugs 69 are engaged in a groove 70 formed about the periphery of a clutch collar 71 whereby pivotal movement of lever 67 is effective to bring 75 about lateral movement of the collar.

The collar is slidably and rotatably supported upon a coupling member 72 which is rotatably supported upon the extending end of floating shaft 20 and has driving connection with the shaft of lower roll 33.

Coupling 72 is provided with a circular opening 73 in its side wall in which a ball 74 is disposed and shaft 20 is provided with a longitudinal groove 75 adapted to receive the ball when in register therewith.

A coil spring 76 normally urges clutch collar 71 toward the left as viewed in Fig. 1.

The collar, when in left hand position, is adapted to cover the opening 73 whereby the ball is prevented from escaping from groove 75. With parts in this position the ball forms a driving connection between shaft 20 and coupling 71.

Movement of the collar to the right, as in Fig. 2 uncovers the opening 73 which permits ball 74 to move outwardly and thus remove the connection between the coupling and shaft 20. With parts so arranged, shaft 20 may rotate freely within coupling 71.

Operation of the described mechanism may be 25 described as follows:

In Fig. 1 all parts are shown in normal position for operating the wringer rolls in a direction determined by manipulation of handle 25, with the wringer locked to its supporting post by pin 14 and clutch collar 71 in position to effect coupling between shaft 20 and roll 33.

With the parts in this position, plunger 53 may be manipulated downwardly to press its head 66 against lever 67 to move the clutch collar toward the right as in Fig. 3 or upwardly to permit spring 76 to propel the collar toward the left to effect driving connection as described. By the above means the wringer may be operated under conditions of ordinary use.

When conditions make it necessary to release 40 the top frame 32 it assumes approximately the position shown in Fig. 3 wherein link 46 has been elevated, carrying lug 48 upwardly to rotate lever 50 to depress extension 52 against link 65 and through this and head 66 to move lever 67 in such 45 a manner as to propel clutch collar 71 toward the right and thereby uncouple the driving mechanism.

It will be noted that plunger 53 has been depressed during the movements described and that 50 the groove 54 is thus brought into alignment with ball 55 whereby the plunger is temporarily retained in depressed position.

The foregoing will illustrate the manner in which release of the top frame automatically 55 brings about de-clutching of the wringer driving means. The driving means will obviously remain de-clutched after the top frame is replaced, as indicated in Fig. 2. The replacing movement places lug 48 in operative engagement with fork 49 to rotate lever 50 into original position, leaving plunger 53 in lowered position, available for normal operation as already explained. It is to be noted that with parts in position shown in 60 Fig. 3, manipulation of plunger 53, to start rotation of the rolls, is prevented by reason of the lug 48 lying opposite extension 49' of lever 50. Obviously, plunger 53 cannot be moved upwardly without rotating lever 50 in clockwise direction 70 and this is made impossible by abutment of portion 49' upon lug 48. In this manner rotation of the rolls is automatically prevented when the parts are not in position for practical use.

An additional de-clutching means is provided 75

in connection with the post-lock mechanism as follows;

When it is desired to swing the wringer upon its post the handle 61 is moved upwardly as in Fig. 3. This movement is effective to withdraw pin 14 out of engagement with collar 11 as shown and also, through arm 62, to move link 65 downwardly to operate the clutch as already described.

Fig. 3 illustrates that driving connection can not be established while handle 61 is in elevated position, but that, by means of the slot 64 the handle may be placed in locking position without operating the clutch into driving position.

In view of the foregoing it is thought apparent that my driving mechanism is adapted to operate in such a manner that releasement of the roll pressure means or unlocking of the wringer head automatically stops the wringer rolls whereby the wringer may be used with maximum safety. The safety feature is enhanced by the peculiar mechanical arrangement which prevents driving connection of the rolls when the parts are not in suitable position for normal use.

What I claim is:

1. A wringer head mechanism comprising, means for driving the wringer rolls, clutching means disposed between the driving means and said rolls, mechanism for releasing pressure between the wringer rolls, a wringer post rotatably supporting the wringer head, mechanism for locking the head relative to the post, and mechanism inter-connecting the locking means, the releasing mechanism and said clutching means whereby release movements of the releasing mechanism or unlocking movement of the locking mechanism brings about operation of the clutching means to stop the wringer rolls.

2. A wringer head mechanism comprising means for driving the wringer rolls, clutching mechanism disposed between said driving means and rolls, a first manually operable means for moving the clutching mechanism to stop the wringer rolls, a wringer post rotatably supporting the wringer head, a second manually operable mechanism for locking the head with respect to the post, the same having connection with said first manual means whereby unlocking movement of the second locking mechanism brings about operation of the first manual means to stop the wringer rolls, said first manually operable means being operable to stop the rolls independently of said post locking mechanism.

3. A device of the class described including in combination a wringer head mechanism, wringer rolls driven thereby, pressure mechanism for the

rolls, a release device releasing pressure on the rolls, a part to be moved as a result of such release, a clutching mechanism disposed between said wringer head mechanism and rolls, a post locking mechanism, a manually operable mechanism capable of operating said clutching mechanism to control rotation of the wringer rolls and mechanism co-operative between the post locking mechanism, said part to be moved and said manually operable mechanism whereby said clutching mechanism may be operated to stop the rolls by means of movement of said released part, movement of said post locking mechanism into unlocked position or said manually operable member severally.

4. A device as set forth in claim 3 wherein the several mentioned mechanisms are capable of operating said clutching mechanism to stop the wringer rolls as described, but wherein the clutching mechanism may be operated to start the rolls exclusively by said manually operable mechanism.

5. A device of the class described including a support post, a wringer mechanism rotatably supported thereon, mechanism for locking the mechanism on the post, wringer rolls, pressure means therefor, release mechanism releasing the pressure means, driving mechanism for the rolls, a clutch between the driving means and rolls, a first means for operating the clutch comprising a connection between said locking mechanism automatically operating said clutch to stop the rolls when the locking mechanism is unlocked, and a second means comprising connection between the releasing mechanism and clutch automatically operating the clutch to stop the rolls when the same are released, said locking mechanism and said releasing mechanism being interconnected for operation of one of the mechanisms upon operation of the other mechanism.

6. In a wringer head mechanism for driving and controlling the rotation of the wringer rolls, a wringer head and wringer rotatably mounted on the wringer post, a manually operable lever for stopping or starting rotation of the rolls, a second manually operable lever for controlling the lock positioning the wringer rotatably on the wringer post, a third manually operable lever for locking or releasing the wringer head and wringer rolls in relation to a wringer post, and an interlocking mechanism connecting these several controls which prevents rotation of the rolls when the wringer is unlocked or open, or when the head is unlocked on the wringer post.

FRED A. PARISH.
